DESIGN FOR A BATHROOM SCALE CASING

John C. Sutton, Rockford, Ill., assignor to The
Bearley Company, Rockford, Ill., a corpora-
tion of Illinois

Application February 23, 1935, Serial No. 55,569

Term of patent 3½ years

To all whom it may concern:

Be it known that I, John C. Sutton, a citizen of the United States, residing at Rockford, in the county of Winnebago and State of Illinois, have invented a new, original, and ornamental Design for a Bathroom Scale Casing, of which the following is a specification, reference being had to the accompanying drawing, forming part thereof.

In the drawing:

Figure 1 is a perspective view of a bathroom scale casing showing my new design;

Fig. 2 is a fragmentary plan view of the front end portion of the casing, and

Fig. 3 is a sectional detail view taken on the line 3—3 of Fig. 2.

The dominant feature of my design consists in the ornamental form surrounding the opening in the platform.

I claim:

The ornamental design for a bathroom scale casing, substantially as shown and described.

JOHN C. SUTTON.
